ABSTRACT OF THE DISCLOSURE

A relay in which a snap acting switch cooperates with a thermally responsive actuating means comprising two bimetallic blade members which provide ambient compensation so that a change in ambient temperature will cause the blades to tend to move in opposite directions against each other. A heater is provided to heat one of the blades to a temperature different than the other blade causing movement of both blades and consequent actuation of the snap acting switch through a motion transfer pin. The heater in one embodiment comprises a plurality of pills constructed of material having a steep-sloped, positive resistivity-temperature curve (PTC) electrically connected in parallel. Another embodiment shows a PTC heater pill mounted on a support with an air gap of a predetermined size separated the heater from the bimetallic blade to provide a time delay of a desired amount. Still another embodiment shows a cantilever mounted support for the heater pill so that the air gap will vary as the bimetallic blade flexes due to heat generated by the heater. The use of the PTC material minimizes the effects of voltage variations on temperature and the use of the air gap as thermal barrier results in voltage compensation.

This invention relates to electrical relays and more particularly to thermal time delay relays.

This invention is an improvement over the relay disclosed and claimed in U.S. Patent No. 3,205,327, issued Sept. 7, 1965 to Moorhead et al. and assigned to the assignee of the instant invention.

The present invention, while having more general uses, is particularly useful in applications for controlling an auxiliary heater for a heat pump (e.g., a space heater) and as a time delay control for air conditioners or for compressors in refrigeration systems.

Among the several objects of this invention may be noted the provision of an improved thermal time delay relay adapted to control an electrical circuit; the provision of such an improved thermal relay which includes ambient compensated thermally responsive actuating means as well as being voltage compensated; the provision of a thermal relay having means to prevent overheating and burn out problems; the provision of such a relay with rapid response; the provision of a thermal relay of the class described which includes snap-acting switch means; and the provision of a time delay relay of the class described which is simple in construction, compact in form and economical to assemble and manufacture.

Other objects and features will be in part apparent and in part pointed out hereinafter.

The invention accordingly comprises the elements and combination of elements, features of construction, and arrangements of parts which will be exemplified in the structures hereinafter described and the scope of which will be indicated in the appended claims.

In the accompanying drawings in which several of the various possible embodiments of the invention are illustrated:

2

FIG. 1 is a top plan view of a switch according to the present invention;

FIG. 2 is an enlarged sectional view taken on line 2—2 of FIG. 1;

FIG. 3 is a bottom plan view of the switch shown in FIG. 1; and

FIG. 4 is a partial top plan view of a second embodiment of the present invention;

FIG. 5 is a vertical cross section taken on line 5—5 of FIG. 4;

FIG. 6 is a view similar to FIG. 5 but showing a third embodiment of the invention; and

FIG. 7 shows resistivity v. temperature curves for several materials useful in our invention.

Similar reference characters indicate corresponding parts throughout the several views of the drawings.

Dimensions of certain of the parts as shown in the drawings may have been modified and/or exaggerated for the purposes of clarity of illustration.

Referring now to FIGS. 2 and 3, there is shown a time delay thermal relay according to the present invention and generally indicated at numeral 10. Relay or switch 10 includes a housing 12 formed of a conventional electrically insulating material such as a moldable phenolic resinous material. As best seen in FIG. 2, housing 12 includes a base 14 and a peripherally extending skirt portion 16 on one side thereof, defining a cavity 18 for reception therein of electrically conductive snap-acting switch means generally indicated at numeral 40. Housing 12 also includes a plurality of upstanding wall portions 20, 22, 24 and 26 on the other side of base 14 which define a cavity 30 for reception of thermally responsive actuator means generally indicated at 70 and which will be described in greater detail below. Cover members (not shown) may be connected to the housing 12 to close cavities 18 and 30 after assembly of switch 10 has been completed.

Snap-acting switch means

Referring now to FIG. 3, snap-acting switch means 40 is received within housing cavity 18 and comprises an electrically conductive flexible blade 42 cantilever mounted adjacent one end 44 thereof, on base 14. End 44 is firmly clamped between, and secured to base 14 and an electrically conductive terminal 46 by means of a rivet 48 which also electrically connects blade 42 to terminal 46. The free end of blade 42 carries a pair of electrical contacts 50 and 52 on opposite sides thereof, as best seen in FIG. 2, for alternate engagement, respectively, with electrical contacts 54 and 56 which are respectively carried by electrical terminals 58 and 60. Housing 12 supports and mounts terminals 58 and 60 on opposite sides of blade 42 and in the path of movement thereof, as best seen in FIGS. 2 and 3. Contacts 50, 52, 54 and 56 are formed of a suitable electrical current-conducting material such as silver or the like. Blade 42 is formed of a suitable highly electrically conductive spring material such as, for example, a beryllium-copper alloy or a Phosphor bronze alloy.

To provide for snap-acting movement of the flexible blade 42 to actuate the contacts, a spring member 62 is provided which is flexed into a U-shaped form (as seen in FIG. 2), with one end thereof connected with the blade 42 adjacent the contact-carrying end thereof, and the other end of the spring member connected with a centrally located tongue 64 formed integrally with the blade 42 as by blanking out portions of the center of the blade. Tongue 64 extends from its integral connection with end 44 of the blade toward the free contact-carrying end of the blade. As best seen in FIGS. 2 and 3, tongue 64, adjacent its interconnection with spring 62, is provided with a dimpled or raised abutment portion 66 for engaging a

motion transfer member to be described in greater detail below.

The tendency of the spring 62 to straighten out urges blade 42 either upwardly or downwardly as seen in FIG. 2, depending upon the position of tongue 64. Snap-acting means 40 can be either of the so-called bistable or monostable types, depending upon the spacing between the stationary contacts 54 and 56 relative to the neutral position of the blade 42, movement beyond which in either direction will cause snap-acting or over-centering movement. Switch means 40, as illustrated by way of example in FIG. 2, is of the monostable type and contacts 52 and 56 are normally closed, so that upon removal of a force applied against tongue 64 to cause snap opening of contacts 52 and 56, blade 42 will automatically snap back to the FIG. 2 solid line position to reclose contacts 52 and 56.

Thermally responsive actuating means

Switch 10 also includes a thermally responsive actuating means generally indicated at numeral 70 for causing snap action of means 40 to effect contact actuation. Means 70 comprises two blade members 72 and 74, each of which are formed of a composite bimetallic thermally responsive material having a relatively high expansion component and a relatively low expansion component, as best seen in FIG. 2. Member 72, as best seen in FIG. 1 is in the form of a frame and provides a substantially rectangular shaped window opening 76 which is defined by four legs 78, 80, 82 and 84. Member 72 can be formed from a sheet by a simple punching or blanking operation. Member 74 is substantially T-shaped and includes a transversely extending end portion 86. As best seen in FIGS. 1 and 2, end portion 86 and leg 84, respectively, of bimetal members 74 and 72 are arranged in stacked overlying relationship and mutually separated by a thermally and electrically insulating strip 90 formed, for example, of mica. This stacked assembly is cantilever mounted on an extension 92 of an electrically conductive terminal member 94 by means of a pair of rivets 96. A thermally and electrically insulating strip 98 (formed, for example, of mica) separates bimetal member 74 from terminal portion 92. Rivets 96 not only serve to firmly cantilever mount the bimetal blade-insulator assembly but also serve to electrically connect bimetal member 72 with terminal 94. A lost motion connection for the other ends of bimetal members or blades 72 and 74 is provided by a bifurcated portion on the other end of member 74 as defined by fingers 102, 104 and 106, which receive and sandwich therebetween, leg 80 of member 72. This connection permits relative sliding movement between the free ends of members 72 and 74 in a direction along the plane of these members, to avoid creating undesirable stresses and also confines upward and downward movement (as seen in FIG. 2) of the free ends of these members to movement in unison. Leg 80 is provided with a dimpled portion 110 which is positioned to engage one end of a motion transfer pin 112 which is slidably received in an aperture 114 provided by base 14 of the housing 12. The other end of pin 112 is positioned to engage the dimpled portion 66 on the central tongue 64 of the snap-acting blade 40 to cause tongue 64 to move in response to unitary movement of bimetal members 72 and 74 to effect snap-acting motion of blade 40.

In practice terminal 94 and bimetal blades 72 and 74 are made up as a separate subassembly which is thereafter mounted on the housing by means of a threaded fastener 100. The bimetal members 74 and 72 are arranged and constructed to provide for ambient compensation. In this regard the inside bimetal components of the blades as are nearest one another or those which face one another, have relatively similar coefficients of thermal expansion, i.e., these components either both have relatively low coefficients of thermal expansion or both have relatively high coefficients of thermal expansion. It is preferred (but not essential) that blades 72 and 74 be

formed of the same or similar bimetal material. It will be seen from the above that when blades 72 and 74 are subjected to a change in ambient temperature (e.g., an increase) that the blades will tend to flex or move in opposite directions against each other which opposing movement will effectively cancel each other out to thereby prevent or at least minimize movement of blades 72 and 74 as a unit in response to changes in ambient temperature. Upon heating of member 74 to a temperature different from that of member 72, member 74 will exert a flexing force against member 72 which is greater than the opposing flexing force exerted by member 72 against member 74, which will cause the free ends of members 72 and 74 to move in unison either downwardly or upwardly depending on whether the inside components of the blades have relatively low or relatively high coefficients of thermal expansion. In the exemplary embodiment shown in the drawings, the inside components of the blades have relatively low coefficients of thermal expansion so that upon suitable differential heating of member 74, downward movement (as seen in FIG. 2) in unison of the free ends of members 72 and 74 will take place.

Relay 10 includes an electrical heater 119 which, in FIGURES 1-3 embodiment, comprises a plurality of pieces or pills 120. Three are shown but the number is a matter of choice. Electrically conducting layers 122 and 124, formed of silver, for example, are attached in a conventional manner to opposite faces of each pill 120.

Pills 120 are located in close thermal juxtaposition to bimetal member 74, and in the FIGS. 1-3 embodiment is electrically separated therefrom by a layer of electrically insulating material 126, which may, for example, be mica. Layers 122 are electrically connected by conductors 125 to an electrically conductive terminal 126 which is located intermediate upstanding portions 24 and 26 of housing 12 and secured to base 14 by means of rivet 127.

Layers 124 are electrically connected by conductors 128 to bimetal member 72 which is in turn electrically connected to terminal 94.

As seen in FIGURE 1, pills 120 are electrically connected in parallel. Pills 120 are constructed of material which has a steep-positive-sloped resistivity-temperature curve (hereinafter referred to as PTC material). This will be explained in greater detail below.

Heater 119 may be mounted, as seen in FIGURES 4 and 5, by mounting pill 120 on layer 132 of an electrical and thermal insulation material such as a polycarbonate, which is separated from bimetal member 74 by portions or bosses 130, 131 to produce an air gap of a predetermined size. The time required for member 74 to flex due to differential heating is dependent upon the thermal conductivity between the heater and member 74. Thus it will be seen that by providing a predetermined thermal insulation barrier between pills 120 and member 74 a given time-delay can be built into the device. The air gap is, of course, a thermal insulator. It will be obvious that other thermal insulation material can be used to effect the same result.

FIGURE 6 shows a similar mounting but utilizes only one mounting portion or boss 131 so that the air gap between heater 119 and bimetal 74 will vary as bimetal 74 flexes due to heat generated by heater 119. Thus great flexibility can be effected in the opening and closing characteristic of the switch by the mounting of the heater elements as described.

Operation of relay 10 is as follows: Contacts 52 and 56 are normally closed, as shown in the FIG. 2 solid line position of the parts. Upon a change in ambient temperature (e.g., an increase) bimetal blades 72 and 74 will tend to flex in directions opposite to each other to produce substantially equal opposing forces with the result that little or no motion of the bimetal members takes place. However, when heater 119 is electrically energized (by the circuit in which terminals 94 and 126 are connected),

member 74 becomes heated to a temperature different from that of member 72. This results in a downward flexure force (as seen in FIG. 2) exerted by member 74 which is greater than the opposing upward flexure force exerted by bimetal member 72 causing downward movement in unison of the free ends of members 74 and 72 from the solid line to the broken line position shown in FIG. 2. This causes motion transfer member 112 to move downwardly (within opening 114) against the dimpled portion 66 of the tongue 64 to move the latter to the FIG. 2 dashed line position to cause over-centering or snap movement of the blade 42 from the FIG. 2 solid line contacts 52, 56 closed, and contacts 50, 54 open position to the FIG. 2 broken line contacts 52, 56 open and contacts 50, 54 closed position. Contacts 50 and 54 will remain closed (in the FIG. 2 broken line position) as long as motion transfer pin 112 is maintained in the broken line position by the forces exerted against it by the bimetal blades 72 and 74. Upon sufficient diminishing of the current in the heater 119, or upon deenergization of the heater, bimetal member 74 will cool and the blades 72 and 74 return to the FIG. 2 solid line position, and blade 42 will automatically snap back to the solid line FIG. 2 position to reclose contacts 52 and 56.

The U-shaped portion of frame 72 defined by legs 78, 80 and 82 which projects from the cantilever mounted end leg 84 advantageously is relatively thermally isolated from heater 119 by the spacing between legs 78 and 82 from blade 74 which is positioned therebetween in the window opening 76, as best seen in FIG. 1. By this arrangement, blade 72 does not become heated to any substantial extent by heater 119. Insulators 90 and 98 further serve to minimize heat transfer between blades 72 and 74 and between heater 119 and blade 72 so that the heat generated by heater 119 is directed primarily to the blade 74 to raise the temperature of the latter above that of the ambient compensating blade 72 to produce desired contact actuating motion of the free ends of these members. However, total thermal isolation between bimetal blade 72 and 74 is not desired because by allowing some heat to be conducted from blade 74 to blade 72, faster resetting of contacts 52, 56 can take place when the heater current is sufficiently diminished or removed. Locating member 74 in the window opening 76 intermediate legs 78 and 82 in addition to providing for a compact construction also permits a substantial portion of the length of blade member 74 to lie substantially in the same plane as or at least very close to the plane of legs 78 and 82, which avoids or at least minimizes creation of undesirable stresses upon temperature change which might tend to twist or rotate the free end of blade 72. This also simplifies the construction and assembly of parts, and provides for compact construction. If desired, leg 84 of blade 72 and portion 86 of blade 74 can be omitted and the unjoined ends of legs 78, 82 and of blade 74 can be cantilever mounted in the same plane on terminal 94 so that a greater portion of member 74 will lie substantially in the same plane with legs 78 and 82 to further minimize creation of undesirable twisting stresses and moments at the free ends of these members 72 and 74, when the latter flex in response to temperature change.

In prior art heaters, such as in the patent to Moorhead et al, referred to supra, the time required to raise the temperature of bimetal 74 to a temperature which will actuate the switch (by Joulean heating of the heater) is directly dependent on the applied voltage since heat generation is proportional to the voltage squared

$$(P=VI=V^2/R)$$

The time required to switch the relay off also depends on the applied voltage since the steady state temperature of the heater also varies as the voltage squared:

$$T_\infty = T_A + \frac{1}{K} \frac{V^2}{R}$$

where

T_∞ =steady state heater temperature
 T_A =ambient temperature
 K =net heat transfer coefficient

Thus a change in voltage will cause a change in the operation of the relay. The actuation time (on time) may, for example, vary as much as 40% for a voltage change of only 10%. The off time will also vary but to a lesser degree. Further, too high voltage can cause overheating and burning of the heater. This is due to the fact that the electrical resistance of such prior art heaters is generally independent of temperature.

In accordance with our invention, a heater is used which electrical resistance increases rapidly in region of the control temperature. Such material include the semi-conducting barium titanate ceramics and certain plastics such as carbon-black loaded, cross-linked polyethylene. FIGURE 7 shows typical resistivity temperature curves. Curve A is for $Ba_{.99}La_{.003}TiO_3$; curve B is for carbon black filled, cross-linked polyethylene; and C is for $Ba_{.909}Pb_{.088}La_{.003}TiO_3$.

Heaters constructed from such PTC materials cannot overheat due to the tremendous increase in resistance over a very narrow temperature range. Such heaters self-heat to the control temperature (located in the near vertical portion of the curves in FIG. 7). A change in voltage causes very little shifting of the curves in FIG. 7 so that the temperature is more or less independent of the applied voltage.

It will be noted that, especially in the FIGURES 4-6 embodiment, if a thermal resistance is interposed between the heater and the bimetal such that the time required to switch the relay on is long compared to the induction time of the heater, voltage compensation is achieved.

It will be seen from the above that the present invention provides for a thermal time delay relay (the time delay resulting from the time interval required for transferring heat from heater 120 to blade 74 and raising its temperature sufficiently to overcome the opposing flexure force of blade 72), which is essentially independent of voltage, has a rapid response time due to the initial low resistance of the PTC element yet has a very high resistance at elevated temperature preventing burning out with higher voltage.

In view of the above, it will be seen that the several objects of the invention are achieved, and other advantageous results attained.

As many changes could be made in the above constructions without departing from the scope of the invention, it is intended that all matter contained in the above description or shown in the accompanying drawings, shall be interpreted as illustrative and not in a limiting sense, and it is also intended that the appended claims shall cover all such equivalent variations as come within the true spirit and scope of the invention.

We claim:

1. A voltage compensated electrical switch comprising a base; contacts mounted on the base; thermostatic means including an elongated thermostatic element mounted on the base to provide contact actuation motion for the contacts; an elongated generally flat support having two ends composed of electrical insulating material; a plurality of bosses of thermal insulation mounting the support to and spacing the support from the thermostatic element; and a heater composed of a steep-sloped PTC material located on the support and separated from the thermostatic element by the support and the spacing whereby the transfer of heat from the heater to the thermostatic element is impeded.

2. A switch according to claim 1 in which the PTC material is selected from the group consisting of carbon black filled, cross-linked polyethylene and doped barium titanate.

3. A switch according to claim 2 in which the doped barium titanate is $Ba_{.99}La_{.003}TiO_3$.

4. A switch according to claim 2 in which the doped barium titanate is $\text{Ba}_{0.909}\text{Pb}_{0.088}\text{La}_{0.003}\text{TiO}_3$.

5. A voltage compensated electrical switch comprising a base; contacts mounted on the base; thermostatic means including an elongated thermostatic element mounted on the base to provide contact actuation motion for the contacts; an elongated generally flat support having two ends composed of thermal and electrical insulating material; a mounting boss located on one end of the support and cantilever connecting the support to the thermostatic element; and a heater located on the support intermediate the boss and the other end and spaced from said bimetal, the heater comprising a steep-sloped PTC element selected from the group consisting of carbon black filled, polyethylene and doped barium titanate, whereby the space between the PTC heater and the thermostatic element will vary with flexing of the thermostatic element.

6. A switch according to claim 5 in which the PTC

element is constructed of a plurality of PTC pills, two electrically conductive layers attached to spaced portions of the pills, and the pills electrically connected in parallel.
